Johnson Kindness PLLC(57) **CLAIM**

The ornamental design for a dental implant reusable bite registration post, as shown and described.

DESCRIPTION

FIG. 1 is a perspective view of the dental implant reusable bite registration post;

FIG. 2 is an elevational view of FIG. 1;

FIG. 3 is a top view of FIG. 1; and,

FIG. 4 is a bottom view of FIG. 1.

Portions of FIGS. 1, 2, and 4 are shown in broken lines for reference purposes, and do not consist of portions of the present design.

1 Claim, 3 Drawing Sheets*Fig. 1.*

Fig.2.
